UNITED STATES PATENT OFFICE

JOHN BODE, OF CHICAGO, ILLINOIS

LAUNDRY RECEPTACLE AND THE LIKE

Application filed April 3, 1930. Serial No. 441,263.

This invention has to do with improvements in laundry receptacles and the like such as are used in homes, apartments, hotel rooms, etc. The features of the invention have been devised with especial reference to the needs and uses of laundry receptacles and the like, but it will presently appear that said features may also be used to advantage in connection with receptacles for other purposes. Inasmuch as the device illustrated and described herein has been designed with especial reference to laundry receptacles I shall refer to the invention in that connection, but in so doing I wish it distinctly understood that I do not thereby intend to limit myself to such use, except as I may do so in the claims.

One feature of the invention relates to the provision of a completely self-contained device which can be installed in the wall of the house or apartment as a unit, and which device when so installed in a unit into which dust and dirt cannot easily find entrance except from the front or open side. That is to say, the device is so arranged that the portion which is set into the wall is completely boxed or enclosed at all points back of the plaster or finish line or surface, so that there is no communication backwards into the interior of the wall. This will also effectively prevent the movement of air and drafts from the interior of the wall through the laundry receptacle into the room or hall where the device is installed. Furthermore, this arrangement will make it possible to build the device as a complete unit which can then be set into place and plastered around when the wall is finished, and without the need of special operations on the part of the contractor or builder.

Another feature of the invention relates to the provision of a device which is provided with an upwardly slidable front wall or closure, which when slid up serves to expose the interior of the receptacle, and allows the laundry contained therein to pass out from the lower end of the device and down onto the floor where it may be gathered up to be removed. In this connection I may state that the body of the device is relatively deep

measured in the vertical direction, and is also relatively thin or shallow measured in the front and back direction, so that it would be very difficult to reach down into the chamber from the top thereof to remove the contained clothes. In fact, in some cases the depth is so great that the bottom cannot be conveniently reached by a person having arms of ordinary length. According to the feature of the invention which is now referred to the front face or wall of the chamber is made vertically slidable so that it can be raised or slid up when the clothes are to be removed, thereby exposing an opening of corresponding size at the bottom of the device, and the clothes will then either naturally slide out from said opening or may be easily pulled out therethrough, since they will of course gravitate to the bottom of the device.

Another feature in connection with the foregoing is to provide an arrangement made of sheet metal having its edge portions refolded or reinforced, but at the same time to provide such an arrangement that there will not be any sharp edges or parts presented at points where they would be likely to catch on the articles of clothing with the disastrous results naturally attendant thereon. It is also a feature of the invention to make similar provision in the construction of the housing or casing which encloses the receptacle, especially in the lower or bottom portion of such housing or casing where the clothes are likely to come into contact therewith.

A further feature of the invention is to provide an arrangement in which there is provided a receptacle which can be tilted forwardly from the wall in order to expose the top for the introduction of the clothes, and also in order to assist in causing the clothes to settle down to the opened lower end of the device when the front wall has been raised to expose the lower end for the removal of the clothes. In other words, this feature has to do with the provision of an arrangement in which the advantages of the forward tiltability are combined with the advantages of ability to slide up or raise the front wall of

the device so as to open the lower end of the receptacle.

Other objects and uses of the invention will appear from a detailed description of the same which consists in the features of invention and combinations of parts herein-after described and claimed.

In the drawings:

Figure 1 shows a perspective view of the device as installed in the wall, the receptacle being in the raised or closed position and with the slide in the lowered or closed position;

Figure 2 shows a view similar to that of Figure 1, with the exception that the receptacle has been tilted forwardly to receive clothes or objects to be introduced therein, the front face being in the lowered or closed position;

Figure 3 shows a vertical section through the complete device, the receptacle being shown in closed position by full lines, and with the front face or slide partially raised in dotted lines, and the receptacle being shown in its forwardly tilted position by means of dotted lines, the slide being in the closed position in such forwardly tilted position;

Figure 4 shows a horizontal section on the line 4—4 of Figure 3 looking in the direction of the arrows;

Figure 5 shows a detailed section through one of the slide connections between the slide and the receptacle proper, being on enlarged scale as compared with the other figures; and

Figure 6 shows a detailed face view of the lower portion of the receptacle on enlarged scale, and it shows the form of pivotal connection between the receptacle proper and the housing, and by dotted lines it shows the manner in which one of the pivot pins can be withdrawn to release the receptacle when needed.

The face of the wall is shown at 7. There is provided a box or housing, generally of sheet metal, and designated in its entirety by the numeral 8. It includes a back sheet 9, and an encircling sheet which provides the sides 10 and 11, and the top and bottom portions 12 and 13. Preferably these sides and top and bottom portions are flared outwardly at the front face of the device so as to establish face flanges which seat against the plaster face and serve to give the device a more complete or finished appearance when installed. These are the flanges 14. It will be noted that when the box like casing or housing is installed in the wall it is completely sealed all around its periphery, and furthermore, that it establishes an enclosed structure which is closed all over its back face so that there are left no openings through which dirt and dust might find their way into the room or hall, and through which drafts might flow.

The receptacle is designated in its entirety by the numeral 15. It includes a back wall 16, bottom 17, and sides 18 and 19. The back and sides may be formed from a single sheet of metal, and the bottom may then be attached thereto by folding, welding, or other suitable operations. The top of the receptacle is left open as shown in Figure 2 in particular.

The front edge of the bottom 17 of the receptacle is folded backwardly as shown in Figure 3 in particular on an angle so that the extreme edge thereof comes into close contact with the bottom face of the bottom of the receptacle, and thus there is provided an arrangement in which the extreme edge of the metal is not only so brought into contact with the large face of the sheet itself, but also the point of such contact is removed to a position where the possibility of catching the cloth of the clothes is reduced to a minimum. This back fold is designated by the numeral 18.

There is a slide 19 which serves to enclose the front of the receptacle. This slide comprises a sheet of metal. Its bottom edge is folded up against the interior face of the slide as shown at 20 in Figure 3, such fold being formed in a manner similar to the folding of the front edge of the bottom 17 already referred to. This fold 20 is presented at the interior face of the front slide, so as to avoid the objectionable appearance which it would otherwise present to the front of the device, but owing to the fact that the extreme edge of the fold 20 is brought into close contact with the face of the sheet itself, the danger of snagging clothes etc., is reduced to a minimum.

The sides edges of the slide, and the front edges of the side walls 18 and 19 of the receptacle are folded outwardly and then reversed as shown in the detail of Figure 5. This produces the interlocking folds which serve to effectively retain the slide in place on the front of the receptacle, while at the same time permitting the slide to be easily slid up and down with respect to the receptacle. Such interlocking sliding connection is designated by the numeral 21. Examination of Figures 1 and 2 shows that these interlocking sliding connections are not objectionable in appearance, and in fact they serve to give the edges of the slide a more or less finished appearance.

The top of the slide is folded inwardly at right angles as best shown in Figure 3 and is then reverse folded so as to provide a horizontal flange 22. This serves to provide a horizontal member which can be easily taken hold of and gripped to raise the slide when so desired. This flange 22 extends the entire width of the slide so that it can be easily taken hold of from almost any position of the user adjacent to the receptacle. It will be

noted from Figure 3 in particular that when the slide is in the fully lowered position its lower edge rests against the front edge of the bottom 17 of the receptacle. Such support is made possible by reason of the fact that the bottom edge of the slide is folded backwardly to establish the fold 20, which therefore lies to the rear of the face of the sheet from which the slide is made.

10 The upper edges of the back and side walls of the receptacle, designated 16, 18 and 19 respectively, are folded downwardly on folds similar to those shown at 18 and 20, and already referred to. These are the folds 23, 24 and 25, best shown in Figures 3 and 2. These folds serve to eliminate sharp edges at the upper end of the receptacle, and thereby reduce the possibility of the clothes being snagged thereon. Furthermore, due to the 20 fact that these folds establish top faces as best shown in Figure 2 the appearance of the receptacle is greatly improved, and the danger of the user injuring his or her hands thereon is eliminated.

25 The lower end of the receptacle is pivoted or hinged to the front edge of the bottom of the housing. Such result is produced by attaching companion eyes or sockets 26 and 27 to the lower end of the receptacle and to the front edge of the bottom of the housing, respectively. Pins such as 28 are then passed through these eyes to complete the hinged connections. These pins can be easily removed when the receptacle is to be removed 30 from the housing.

If desired, a knob or handle 29 can be placed on the upper portion of the front face of the receptacle so that the receptacle can be easily pulled forwards when its upper 40 end is to be exposed. There is provided a shelf 30 which extends across the upper portion of the housing immediately above the top of the receptacle when the latter is in the upright position. This shelf comprises a sheet of metal which is the full width of the housing, and reaches forwards beyond the front edge of the housing an amount slightly greater than the projection of the receptacle therebeyond. The front edge of 45 this shelf is turned downwardly as shown at 31 to establish a flange; and the rear upper edge of the receptacle is provided with one or more upwardly extending pins or lugs 32 (see Figure 3 in particular), which engage 50 against the said flange when the receptacle is tilted forwards. These lugs serve to limit the forward tilting movement and hold the receptacle in the open position.

55 Preferably the slide is perforated with perforations on an attractive design as best shown in Figures 1 and 2, such perforations serving to effectively ventilate the interior of the receptacle and prevent it from becoming foul. Similar perforations may also be provided in the back wall or face of the re-

ceptacle so as to allow a complete through movement of the ventilating air.

It will be evident that the use of a slidable front wall for the receptacle bears a peculiar relationship to the forward tiltability of said receptacle, since, by tilting the receptacle forwards, and at the same time raising the slide, the clothes are caused to rest against the lower front portion of the receptacle so that the raising of the slide allows them to move naturally outwards onto the floor, or into the hands of the user. Nevertheless, the slide can be raised when the receptacle is in the closed position, or with a very slight amount of forward tilt to allow the upper edge of the slide to pass the shelf, in which case the clothes may be easily reached and pulled out of the lower end of the receptacle.

While I have herein shown and described only a single embodiment of the features of my present invention, still I do not intend to limit myself thereto except as I may do so in the claims.

I claim;

1. In a device of the class described, the combination of a housing comprising a box like structure open on its front face and closed on its back, top, bottom and sides, and provided with an outwardly extending encircling flange adapted to seat at the plaster line of the wall, and a receptacle for clothes and the like working in said housing, said receptacle comprising a box like structure including a back, bottom, and sides, together with a front wall slidably connected to the front edges of the sides aforesaid to permit up and down sliding of said front wall with respect to the receptacle, the bottom edge of the slidable front wall being inturned to overlie the front edge of the bottom of the receptacle and serve as a stop for downward movement of the front wall when lowered to close the front of the receptacle, a hinged connection between the bottom of the receptacle and the front edge of the bottom of the housing permitting the receptacle to be tilted forwards with respect to the housing, and means for limiting the tilting movement aforesaid, substantially as described.

2. In a device of the class described, the combination of a housing comprising a box like structure open on its front face and closed on its back, top, bottom and sides, and provided with an outwardly extending encircling flange adapted to seat at the plaster line of the wall, and a receptacle for clothes and the like working in said housing, said receptacle comprising a box like structure including a back, bottom and sides, together with a front wall slidably connected to the front edges of the side aforesaid to permit up and down sliding of said front wall with respect to the receptacle, the bottom edge of the slidable front wall being

inturned to overlie the front edge of the bottom of the receptacle and serve as a stop for downward movement of the front wall when lowered to close the front of the receptacle, and a hinged connection between the bottom of the receptacle and the front edge of the bottom of the housing permitting the receptacle to be tilted forwardly with respect to the housing, substantially as described.

19 3. In a device of the class described, the combination of a housing comprising a box like structure open on its front face and closed on its back, top, bottom and sides, and provided with an outwardly extending 15 encircling flange adapted to seat at the plaster line of the wall, and a receptacle for clothes and the like working, in said housing, said receptacle comprising a box like structure including a back, bottom and sides and 20 being open on its entire front face, together with a unitary front wall slidably connected to the front edges of the sides aforesaid to permit up and down sliding of said front wall with respect to the receptacle to expose 25 the bottom portion of the front face and give access thereto, and a hinged connection between the bottom of the receptacle and the front edge of the bottom of the housing permitting the receptacle to be tilted forwardly with respect to the housing, substantially as described.

JOHN BODE.
